LUMINOUS DISCHARGE TUBE

Miles Pennybacker, West Orange, and Albert R. Hussey, Lyndhurst, N. J.; said Hussey assignor to said Pennybacker

Application October 28, 1942, Serial No. 463,598

1 Claim. (Cl. 315—73)

This invention relates to gas discharge devices, such as lamps, of the hot cathode type, and relates more particularly to devices of this character provided with internal thermostatically operated starting switches and intended to be operated upon commercial lighting circuits with auxiliary ballasts or transformers whereby the voltages impressed upon the devices during striking are of the order of 100 to 500 volts.

One object of our invention is to provide a gas discharge device of the foregoing character which shall have a reasonably long life, which is capable of operation at usual commercial voltages, and which is capable of quick starting and quick re-starting. These features are essential in commercially acceptable fluorescent lamps for illuminating purposes, in which field our invention finds particular utility.

Another purpose of our invention is to provide, in such devices novel means for shielding the contact points of the internal switching mechanism, whereby deleterious discharges between the contact points themselves, or between the hot cathode and any portion of the internal switching mechanism are prevented.

According to present practice in the art, each fluorescent lamp is intended to be operated in conjunction with a separate external starting switch. This starting switch, which is usually automatic in its action, provides a pre-heating current through the filamentary cathodes of the lamp whenever the manual switch is closed, and after a predetermined time has elapsed during which such pre-heating takes place, the switch opens the filament circuit and substantially simultaneously a sufficient voltage is impressed across the terminals of the lamp in order to establish therein a self-sustaining gas discharge.

In the types of switches commonly employed in the art, this pre-heating of the filament and the opening of the filament circuit, if the lamp requires a higher starting voltage than that available, is followed by reclosure of the switch and successive repetition of the starting cycle.

An abnormally high starting voltage typically occurs after 100 to 3,000 hours of operation, and is the usual cause of lamp failure or "burn out." If allowed to continue this repetition of the starting cycle, the switch will continue successively to function until wear upon the elements thereof brings about its premature destruction. Failure promptly to remove an inoperative lamp demanding such high starting voltage, therefore greatly shortens the effective life of the switch. An imperfect or damaged switch will shorten the life

of any new lamp with which it may be operated, because either too long or too short a pre-heating interval has a deleterious effect on the filament coating and hence on the starting voltage required by the lamp; therefore replacement of lamp only, without replacement of switch, frequently results in shortened lamp life.

Due to necessary tolerances in production, and to variations between the lamps of different manufacturers, the characteristics of the lamps and the switches are not now accurately matched to one another for optimum results, even when such devices are new.

It would be impractical to require users to buy them in matched pairs, and always to replace the more or less damaged switch whenever a lamp replacement is made, although this procedure would result in a great improvement in the average life of fluorescent lamps.

15 An internal starting switch, built integrally with the lamp, does more than make possible an accurately matched new switch with each new lamp. It avoids the necessity of extra parts such as the switch socket and terminals and the switch 20 housing required for a separate replaceable switch. It also permits the switch to be closely associated with, and directly controlled by the cathode temperature, thus providing an optimum discharge starting temperature, despite manufacturing variations which may occur in the characteristics of the lamp cathode, or the associated lamp ballast. Even abnormal fluctuations of line 25 voltages do not materially alter the filament temperature at which the herein described internal switch will open.

30 Prior internal starting switches have not been commercially successful because the voltages required to start most fluorescent lamps are sufficiently high to cause a discharge to strike between a hot cathode and a switch terminal of opposite polarity, if said terminal be exposed within the interior of the lamp and substantially nearer to said cathode than other electrodes of the lamp. The initiation of this objectionable discharge to the switch terminal is abetted by the 35 fact that an ancillary discharge is apt to take place between opposing ends of the filamentary electrode just prior to the opening of the starting switch, thus providing conditions suitable for establishing a relatively low voltage discharge in that vicinity. While this ancillary discharge may be desirable in facilitating the initiation of the main discharge in the lamp, yet the presence of gas ionization due to such ancillary discharge

tends to promote the establishment of the undesired and objectionable arc above referred to.

With the shielded or enclosed starting switch of this invention, the formation of any discharge between the hot cathode and a nearby switch terminal is completely prevented, even when potentials as high as 500 volts are applied to the lamp. In order to take advantage of the formation of an ancillary discharge across portions of the filamentary electrode, it is possible to adjust the thermostat controlling the starting switch of this invention, so that the contact points will not separate from one another until the filamentary electrode has reached a temperature sufficiently high to initiate such ancillary discharge.

Our invention improves upon the prior art by providing a simple and practical means of making the internal starting switch workable in discharge tubes, the relatively high starting voltage of which would otherwise cause discharge to one of the switch terminals.

Other objects and features of our invention may be understood from the following description when read with reference to the accompanying drawing, in which:

Fig. 1 is a view in side elevation of one end of the lamp, with the envelope broken away so as to show in detail the electrode and starting switch of this invention.

Fig. 2 shows the device of Fig. 1 as seen from the left side.

Fig. 3 is a schematic circuit showing one manner in which all electrodes of the lamp as well as the starting switch may be connected to an external source of electrical energy and to external ancillary devices such as an inductive ballast.

The starting switch of this invention is preferably mounted at one end of the lamp, as shown in Figs. 1 and 2. The filamentary electrode 10 is mounted so as to be stretched between support wires 11 and 12. Wire 11 is embedded in the glass press 13, but serves only as a mechanical support for this end of the filament. Support wire 12 is likewise mounted in the glass press and a connecting wire extends from this support wire to pin 14 extending from the lamp base 29 and serving as one of the pins supporting the tube in a socket and affording electrical connection to the interior of the lamp.

The glass press 13 is provided with an extension 15' in the form of a glass tube. From the other external pin 15, a lead wire 16 extends into the lower portion of tube 15', where it forms one contact point of the starting switch. The wire constituting the upper contact point 16', of this switch lies in the upper portion of the tube and emerges from the top thereof, at which point the wire is bent back reversely as indicated at 17. This reversely bent portion has affixed thereto by any convenient means such as welding, a U-formed bimetallic thermostat 18 extending toward press 13. The lower portion of thermostat 18 is mechanically and electrically coupled by means of a short length of stiff wire 19 to the upper end of a second U-formed bimetallic thermostat 20. The lower end of thermostat 20 is affixed to a stiff wire 21 which in turn is welded to support wire 11. This wire 21 extends in a direction parallel to the filamentary electrode and the lower end of thermostat 20 is supported thereby. Thermostat 20 is the main thermostat. It is in close proximity to the electrode 10 so as to be quickly responsive to the temperature thereof, and when heated it opens switch contacts 16-16'. Thermostat 18 is more remote from the electrode, and

opposes the action of the main thermostat 20, for a purpose later to be described.

The other end of the lamp of this invention, as shown in Fig. 3, can be formed in the conventional fashion and may include a filamentary electrode 22 connected to external supporting and conducting pins 23 and 24 at the respective ends of this electrode. Since no external starting switch is required for this lamp, pin 15 may be connected by an external conductor 25 to pin 24, located at the other extremity of the lamp. Pins 14 and 23 are connected by the respective external conductors 26 and 27 to auto-transformer 28, fed from a suitable source of electrical energy as indicated by the legend 110v. In lieu of employing an auto-transformer, direct connection to the power supply may be used and in series with one of the external conductors, for example conductor 27, there may be inserted, as well-known in the art, any suitable choke or ballast coil. It is to be understood that no particular method of compensating for the negative resistance characteristic of the lamp is demanded by our invention and forms no essential part of the instant invention and that in its place there may be used ballast resistors, transformers or the like, as well-known in the fluorescent lamp art.

It can be seen that while pins 23 and 24 are electrically symmetrical, pins 14 and 15 are not symmetrical with respect to their electrical connections. Therefore this lamp must be so inserted in the socket that pin 14 shall be connected to one side of the source of external energy. However if the polarized lamp be inserted in the wrong sense, electrically, into the socket, while it will fail to function normally, yet no permanent damage can result from such wrong insertion. Turning the lamp through 180° around its axis will correct wrong insertion when it occurs, or the lamp and sockets may be marked to indicate correct insertion angular positions.

It will be noted that the main thermostat 20 is placed in thermal proximity to the end of the filamentary electrode 10 which latter is at all times, during normal operation of the lamp, connected through support wire 12 and pin 14 to one side of the energy supply circuit. It is this end of the electrode which remains heated by the main discharge from the lamp, after the starting sequence has been completed, and in this manner the thermostatic element 20 continues to be heated, even after the pre-heating circuit has been broken by the separation of the contact points within insulating tube 15'. It is to be noted that main thermostat 20 and compensating thermostat 18 are so constructed as to act in opposition to one another, and since they do not depend upon current flow therethrough for their operation, they may be made of comparatively low electrical resistance.

Upon closing the connections to the source of external energy, the current path may be traced as follows: through conductor 27, choke coil 28, pin 23, filamentary electrode 22, pin 24, conductor 25, pin 15, contact wires 16 and 16', compensating thermostat 18, connecting link wire 19, main thermostat 20, support wire 21, support wire 11, filamentary electrode 10, support wire 12, pin 14, and conductor 28, back to the source of energy supply. This wholly metallic pre-heated circuit causes filamentary electrodes 10 and 22 rapidly to become heated to the point where sufficient electron emission for lamp operation is secured therefrom. At the same time, the heating of electrode 10 causes the transfer of heat to main ther-

mostat 20, mainly by radiation. The operation of thermostat 20 causes the upper end thereof to move away from support wire 21, thus raising compensating thermostat 18, lead wire 17 and therefore also raising upper contact point 16' from lower contact point 16. The interruption of the circuit, at this point, causes the establishment of the main discharge within the lamp, between electrodes 10 and 22. This main discharge continues to maintain thermostatic element 20 in a heated condition, as previously explained. As compensating thermostat 18 becomes heated, at a somewhat later time, due to the fact that it cannot derive heat directly from filament 10, it will operate in the opposite sense to that in which main thermostat 20 operates. Therefore it will tend to compensate for the rather high steady state temperature assumed by main thermostat 20 during normal operation of the lamp and will prevent too great an open-circuit separation between the contact points 16 and 16'. This means that if a lamp be turned off and then be turned on again very shortly thereafter, the thermostat 20 will not need to cool to the same temperature as it would necessarily be when the lamp was cold, because compensating thermostat 18 has meanwhile acted to raise the temperature at which the contact points 16 and 16' will make contact with one another, as previously explained. Likewise a change of the ambient temperature to which the lamp may be subjected while cold will cause thermostats 18 and 20 to act in opposite senses, so that the rise of temperature necessary to actuate the main switch contact will not be substantially affected by such change of ambient temperature. This compensating action of thermostat 18, while desirable in fluorescent lamps, is by no means essential, and our invention may be constructed in a form omitting such compensating thermostat, if so desired.

In Fig. 3 there is shown no external starting switch. Such switch, if already present in an existing installation in which the lamp of this invention is to be used, may be shorted out if so desired, or may be left in circuit. In the latter case, an external starting switch will not prevent the proper functioning of the switch of this invention, but merely will be a superfluous element in the circuit as a whole.

It has been found unnecessary to have an extremely close fit between moveable contact point 16' and the interior walls of tube 15', within which it moves. However it has been found desirable to make the distance between the point at which the contacts separate from one another and the upper extremity of tube 15', as great as possible. The greater that this distance is made, the looser can be the fit between contact 16' and tube 15', for a given voltage.

In order to avoid welding of the contact points, 60

it has been found desirable to make the respective points of different materials, but it has been found possible to use relatively inexpensive materials, such as copper and silver, for these contact points.

In case that it be desired to form the lamp of this invention with a single external contact pin at each end, conductor 25 may extend wholly within the tube, from one end of filamentary electrode 22, at one end of the tube, to lead wire 16 at the other end thereof, with such shielding as may be required. In this case pins 15 and 24 may be dispensed with, so that there will be but a single pin at each end of the tube. Alternatively, pins 15 and 24 may be retained and electrically connected with the adjacent pins inside the base 29, thus utilizing standard bases and sockets. As a further development of this form of construction, still another lead, with any needed shielding, may extend from the opposite end of filamentary electrode 22, through the length of the tube, so as to allow pin 23 to appear upon the same end of the tube as does pin 14, thereby demanding the use of only a single socket in order to afford mechanical support for and electrical connection with the lamp.

While we have described our invention with reference to lamps similar to the 30 and 40 watt commercial fluorescent lamps which start at voltages of the order of 200, it is to be understood that our invention is applicable to other lamps, and to tubes having purposes other than lighting.

We claim:

35 A hot electrode gas discharge lamp capable of rapid restarting if extinguished while hot, including in combination a starting device comprising a thermostat responsive to the temperature of said electrode, a switch operated by said thermostat for interrupting the pre-heating electric current when said electrode reaches a predetermined temperature, and means for shielding one contact of said switch from said electrode, whereby deleterious discharge to said switch contact is avoided, and including means for establishing a main gas discharge to said electrode upon the interruption of said pre-heating electric current by said switch, also including a second thermostat acting oppositely to the first thermostat and 40 relatively remote from said electrode, so as to be less responsive to the temperature of said electrode, said switch having its operation determined by the joint effect of both thermostats, whereby 45 rapid restarting of the gas discharge device is facilitated, and whereby said electrode constitutes 50 the only heating element needed to operate said switch.

MILES PENNYBACKER.
